The ornamental design for a cylindrical balloon lamp, as shown and described.

DESCRIPTION

FIG. 1 is a perspective view of a cylindrical balloon lamp showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown in the drawings are for the purpose of illustrating portions of the cylindrical balloon lamp and form no part of the claimed design.
